FRANK CONRAD, OF SWISSVALE, PENNSYLVANIA, ASSIGNOR TO WESTINGHOUSE ELECTRIC AND MANUFACTURING COMPANY, A CORPORATION OF PENNSYLVANIA.

STARTING MEANS FOR VAPOR ELECTRIC DEVICES.

1,166,186.

Specification of Letters Patent. Patented Dec. 28, 1915.

Application filed January 7, 1912. Serial No. 601,391.

To all whom it may concern:

Be it known that I, FRANK CONRAD, a citizen of the United States, and a resident of Swissvale, in the county of Allegheny and State of Pennsylvania, have invented a new and useful Improvement in Starting Means for Vapor Electric Devices, of which the following is a specification.

My invention relates to starting means for vapor electric devices, such as current rectifiers and lamps, in which mercury is employed as a vaporizable electrode, and it has for its object to provide means whereby a starting electrode may be moved into and out of engagement with the mercury or other vaporizable electrode, which means shall be accessible for operation from the exterior of the rectifier casing.

Figure 1 of the accompanying drawing is a sectional view through a part of a mercury vapor rectifier that embodies my invention, and Fig. 2 is a side view of certain of the operatively related parts for actuating the movable starting electrode.

The device in connection with which the present invention is employed is a mercury vapor rectifier having an iron or other suitable metallic casing 1 upon which a cover 2 is tightly clamped, the top portion of the casing being provided with a tapered or frusto-conical seat that is engaged by a correspondingly shaped portion of the cover. Within the casing is an insulating bowl or cup 3 that is suitably composed of porcelain or quartz and contains a body 4 of mercury or any other suitable material constituting a vaporizable electrode.

The cover 2 is provided with a sleeve 5 having an interior tapered seat 6 at its lower end for the reception of a correspondingly shaped exterior portion of an insulating bushing 7 that extends through the cover and into the chamber within the casing. The bushing 7 is secured in the cover 2 by means of a sleeve or nut 8 that is screwed into the upper end of the sleeve 5 and between which and a shoulder upon the bushing 7, an asbestos or other slightly compressible washer 9 is interposed, metallic washers 10 being located above and below the washer 9 for protecting the same. The asbestos washer provides means whereby the

pressure exerted by the nut 8 is distributed substantially uniformly upon the surface of the shoulder on the bushing 7. 55

The bushing 7 is provided with an interior tapered or frusto-conical seat 12 for the lower face of an enlargement 13^a of a tubular iron member 13 that extends from near the top of the bushing 7, through the same, and 60 into the chamber within the casing. Resting upon the shoulder provided by the upper face of the enlargement 13^a of the tubular member 13 is an insulating sleeve 14 by means of which pressure is transmitted to the said 65 shoulder for forcing the tapered lower face of the enlargement 13^a of the member 13 against the seat in the bushing 7. Pressure is applied to the sleeve 14 by means of a 70 tubular nut 16 having an external screw-thread engagement with a bushing 17 that is cemented or otherwise secured in the upper end of the bushing 7, an asbestos or other suitable slightly compressible washer 18 and metallic washers 19 being interposed between 75 the nut 16 and the sleeve 14. The tubular member 13 is also provided with an interior tapered or frusto-conical seat 21 for the reception of a correspondingly shaped face upon a local enlargement 22^b of a rod 22 that 80 extends entirely through all of the surrounding parts, the said rod being provided, upon its upper end, with a head or knot 23, or other suitable means, for conveniently effecting rotation thereof. Near its upper end, 85 the rod 22 is locally enlarged to provide a shoulder or seat 24 between which and the upper end of the tubular nut 16 is interposed a spring 25 for forcing the enlargement 22^b of the rod 22 upon the seat 21 in the tubular 90 member 13. A flexible connection 26 is employed for establishing a good electrical connection between the nut 16 and the rod 22.

The parts above described are so shaped as to provide spaces directly above the places 95 where the parts are seated, the against the other, and the said spaces are filled, or partially filled, with mercury or any other suitable material for rendering the joints more nearly vacuum tight than they otherwise 100 would be. The tubular member 13 and the sleeve 14 are provided with apertures which permit mercury to flow into all of the spaces between the adjacent parts, and the nut 16 is

provided with longitudinal passages 15 through which mercury may be poured into the said spaces.

One end of a lever 30 is pivotally attached 5 to the lower end of the tubular member 13 and from its other end is pivotally suspended a rod 31, upon the lower free end of which is a carbon or other suitable terminal member 32 that constitutes a starting 10 electrode and is adapted to be moved into and out of the mercury 4 by rotation of the rod 22. The under side of the lever 30 is provided with a roller 33 that is disposed parallel to its longitudinal axis to engage a 15 cam 34 which is rigidly mounted upon the lower end of the rod 22. Rotation of the cam 34 by means of the knob 23 and the rod 22 serves to raise and lower the lever 30 and, with it, the rod 31 and terminal member 32. 20 The rod 31 is guided in its vertical movement by means of an apertured bracket arm 35 that is secured to the lower end of the tubular member 13.

In order to start the rectifying process 25 within the device, the knob 23 is turned to cause the starting electrode 32 to be lowered into the mercury 4 and to be subsequently withdrawn therefrom, whereupon an arc is produced which overcomes the negative electrode 30 resistance and permits the rectifying process to start. It will, of course, be understood that, during this operation, the terminals of a suitable source of energy (not shown) are connected, respectively, to the 35 vaporizable electrode 4 and the starting electrode 32. When the rectifier is in operation, the starting electrode 32 occupies the position shown in full lines.

I claim as my invention:

40 1. In a vapor electric device, the combination with an evacuated container, of a movable electrode therein, a member for manipulating said electrode and extending through

the wall of said container, and a seal having a total length of less than 760 millimeters 45 for providing a vacuum-tight joint between said member and the wall of said container.

2. In a vapor electric device, the combination with a casing, of a bushing extending into the casing, a tubular member seated in 50 the bushing and extending through the same into the casing, a rotatable rod seated in and extending through the tubular member, an electrode within the casing, and means associated with said tubular member and said 55 rod whereby rotation of the said rod raises and lowers the electrode.

3. In a vapor electric device, the combination with a casing, of a bushing extending into the casing, a tubular member seated in 60 the bushing and extending through the same into the casing, a rotatable rod seated in and extending through the tubular member, an electrode within the casing, and means whereby rotation of the said rod raises and 65 lowers the electrode.

4. In a vapor electric device, the combination with a casing, of a bushing extending into the casing, a tubular member seated in the bushing and extending through the same 70 into the casing, means for forcing the tubular member upon the seat in the bushing, a rotatable rod seated in and extending through the tubular member, means for resiliently holding the rotatable rod to its seat 75 in the tubular member, an electrode within the casing, and means whereby rotation of the said rod raises and lowers the electrode.

In testimony whereof, I have hereunto subscribed my name this 30th day of Dec., 80 1910.

FRANK CONRAD.
